Des. 217,375
Patented Apr. 28, 1970

217,375

ROCKING TOY

Raymond J. Lohr and Charles M. Kienholz, Erie, Pa.,
assignors to Louis Marx & Co., Inc.

Filed June 20, 1969, Ser. No. 17,798

Term of patent 14 years

Int. Cl. D21—02

U.S. Cl. D34—5

FIG. 1

FIG. 2

FIG. 3

FIG. 4

FIG. 1 is a front perspective view of rocking toy in accordance with our new design;

FIG. 2 is a bottom plane view thereof;

FIG. 3 is a side elevational view thereof; and

FIG. 4 is a view similar to FIG. 3 showing the opposite side thereof.

We claim:

The ornamental design for a rocking toy, as shown.
